United States Patent Office

Des. 177,431
Patented Apr. 10, 1956

177,431

TEXTILE FABRIC

Patricia Ann Prichard, New York, N. Y., assignor to E-Z
Mills, Incorporated, New York, N. Y., a corporation of
New York

Application April 28, 1955, Serial No. 35,729

Term of patent 3½ years

(Cl. D92—1)

The figure is a plan view of the textile fabric showing my new design.

I claim:

The ornamental design for a textile fabric, substantially as shown.
